HAIR CURLER

Nathan L. Solomon, Brooklyn, N. Y.

Application November 14, 1936, Serial No. 110,807

28 Claims.

(Cl. 132—33)

The subject matter of the present invention is an improved hair curler of the type having hingedly associated hair clamping components about which hair is spirally wound and an important object thereof is to provide rotatable means journaled in one of said components to removably sustain the normally closed juxtaposed arms of a hair pin widely separated to conveniently permit transfer of the spirally wound hair or curl about the components therefrom to one of the arms of the hair pin. The invention has as another object the provision of rotatable means journaled in one of the components and having means for removably holding a corrugated arm of the hair pin on a bias and spaced from the rectilinear arm of the hair pin whereby the hair curled about the components may be slidably shifted to be free of the components and arranged or threaded on the rectilinear arm whereby upon separation of the hair pin from the rotatable means the corrugated arm of the hair pin automatically retracts and serves as clamping means to hold the curl on the rectilinear arm. The invention has as a further object, the provision of a serviceable and novel hair curler characterized by a relatively elongated tube having hingedly attached thereto a clamping cover, the tube serving as a bearing to rotatably sustain unitary means in the form of a plug or barrel having a longitudinally disposed opening for removably retaining one arm of a hair pin and having an accessible grooved portion for removably holding another arm of the hair pin on a bias or widely spaced from its companion rectilinear arm.

To enable others skilled in the art to fully comprehend the underlying features of the invention that they may embody the same in numerous modifications in structural and functional relation contemplated by this invention, a drawing depicting preferred and modified forms has been annexed hereto as a part of this disclosure, and in such drawing like characters of reference denote corresponding parts throughout all of the views, of which:

Fig. 1 is a side view of the curler according to my invention illustrating the cover thereof open and the removable hair pin mounted on the rotatable barrel carried by the tube of the curler.

Fig. 2 is a longitudinal sectional view of the hair curler illustrated in Fig. 1, however the curler is shown closed clamping a portion of the hair wound about the tube and itself, the legs or shanks of the hair pin however being shown

widely separated and retained by the rotatable barrel or closure.

Fig. 3 is a perspective view of the barrel or closure shown in Fig. 1.

Fig. 4 illustrates a longitudinal and sectional view of a modified embodiment according to the invention in which the barrel or closure is in the form of an elongated substantially cylindrical member having its rear portion rotatably anchored within and at the rear end of the curler, and

Fig. 5 is a view of several curls formed by the curler herein.

Illustrative of the embodiments disclosed, the hair curler 10 embodies complementary and hingedly associated components 11 and 12. Component 11 is in the form of an elongated tube. If desired, this tube may be slightly tapered as shown.

Extending transversely of the tube and sustained thereby at the rear end thereof is a fulcrum pin 13 on which perforated depending ears 14 of the component or inverted substantially U shaped cover or bar 12 is swingably mounted. Thereafter the ends of pin 13 are upset to form heads 15 to prevent lateral displacement of the cover relative to relatively elongated tube 11.

The rear manipulatable ends of tube and cover each comprise an inwardly turned terminal portion or lip 16 for holding the crown 17 of the U shaped spring 18 against the traverse pin 13. The arms of this spring urge the rear ends of the curler outwardly to normally hold the front ends thereof closed.

According to the form illustrated in Figs. 1 and 2, the tube is grooved to provide an annular flange or indentation 19 pressed inwardly thereof to constitute a stop to limit the insertion of the expanded part 20 of a plug or closure 21 having a reduced portion 22 defining with expanded part 20 an annular shoulder 23 over which is bent annular lip 24 of the forward end or part of the tube, the arrangement being such that lip 24 coacts with shoulder 23 to prevent longitudinal displacement of the rotatable closure or barrel in an outward direction relative to the tube which in effect has its forward part, that is, the part between indentation 19 and lip 24, serving as a bearing in which the expanded portion of the plug is journaled or rotatably sustained.

The reduced part 22 of the rotatable closure or barrel extends or projects beyond the forward part of the tube thus constituting a head therefor, however, provided with a relatively restricted but elongated eccentrically disposed bore

25 coextensive with the length thereof to removably but slidably retain rectilinear arm or shank 26 of a hair pin or hair pin loop 27 having its other companion ribbed or corrugated arm 28 removably retained on a bias in an inclined groove 29, that is, a portion of arm or shank 28 is removably interlocked with the side walls of the tip, end or closure, or barrel 21, the arms 26 and 28 of the hair pin being resiliently connected as shown and as is well understood in the art to normally hold these arms in contact or closed.

By the present arrangement it will be observed, that the arms of the hair pin loop may be retained in a widely diverged relation by the head of barrel 22 which also has the additional function of serving as a closure for the tube of the curler.

In operation, an unloaded hair pin is first mounted on the closure or barrel by inserting one arm thereof in opening 25 and by locking the other arm in the slot or groove 29. Having positioned the hair pin against rotation in respect to the unitary means or barrel 21, the hair pin is manually but slidably moved longitudinally of the barrel and towards the rear of the curler, being slidably guided during such operation by bore 25 and notch 29. The hair pin is now in the position shown in Fig. 2 wherein the free end of arm 28 of the pin is widely spaced from the curler while the intermediate portion of arm 28 is disconnectably locked in notch 29 and thus prevents rotation of the hair pin relative to the barrel. The curler is then opened by pressing the rear ends thereof against the resistance of spring 18. The free ends of the hair to be curled are inserted between the cover and tube. Finger pressure is removed from the rear ends of the curler. The spring releases and the cover closes, clamping the uncurled hair against the tube. The curler is then revolved about the longitudinal axis thereof but relative to the closure or roller 21 to spirally wind the hair thereabout to form curl 30. Subsequently the curl may be slidably moved along the closed curler towards the front end thereof and until it is free of the reduced part or head of the rotatable closure. Since the rectilinear arm 26 of the hair pin loop in part extends through the head 22 during displacement of the curl 30, this curl when free of head 22 will be transferred and threaded onto the rectilinear arm 26 and during such transfer of the curl from the curler to the hair pin, the free portion of arm 28 of the pin is laterally or outwardly displaced in respect to the barrel or head 21 of the curler by the shifted curl. Thereafter the hair pin loop is grasped and slidably and bodily removed from the rotatable head or closure.

Pursuant to removal or disengagement of the hair pin loop from the rotatable head, the corrugated or reinforced arm automatically retracts or closes and resiliently clamps and holds the curl now threaded on the rectilinear arm of the loop. Hence it is apparent that although the curl is formed by revolving the swingable complements 11 and 12 relative to the closure, the curl after forming thereof may be readily transferred to the hair pin to be clamped by the latter but free of the curler.

In the form illustrated in Fig. 4, the closure or barrel 22 is rotatably anchored at the rear end of the curler. In this connection, it will be observed that a sleeve or bushing 30 is disposed within tube 11 of the curler. This sleeve has an expanded annular portion 31 provided with

spaced ears 31' mounted on the transverse fulcrum pin 13 which serves to prevent longitudinal displacement of the sleeve. Sleeve 30 also includes a reduced portion 32 defining an annular shoulder 33 with its expanded complementary portion 31.

The inner expanded part 20 of the closure 21 is rotatably mounted within the expanded part 31 of the sleeve 30 and annular shoulder 33 of the sleeve cooperates with annular shoulder 23 of the closure to prevent longitudinal displacement of the latter in one direction while the transverse pin 13 cooperates with the expanded part 20 of the closure to prevent longitudinal displacement of the latter in an opposite direction.

Sleeve or insert 30 in effect is a bearing for the rear part of the rotatable closure 21 while the front inwardly turned lip or rim 24 rotatably supports and guides the reduced part or head 22 of the closure which overhangs the front end of the tube 11 and is provided with the eccentrically disposed bore 25 as in the case of the embodiment shown in Figs. 1 and 2 for removably holding one arm of a hair pin or hair pin loop while the biased groove 29 is utilized to anchor or retain the other arm of the hair pin to permit the transfer of a curl after having been wound on the loop and to be clamped thereby and be independent of the curler as clearly illustrated in Fig. 5.

While the invention has been described in detail and reference has been made to specific applications thereof, it is to be understood that the invention herein disclosed is not limited to such specific applications and it is intended that all matter contained in the above description and shown in the accompanying drawing shall be interpreted as illustrative and not in a limiting sense.

What I claim is:

1. In combination, hingedly associated complementary hair clamping components, a hair pin, and a member rotatably carried by one of said components and having means for removably sustaining the arms of said pin widely separated.

2. In combination, hingedly associated complementary hair clamping components, a hair pin comprising a pair of juxtaposed arms, a barrel, and means rotatably guiding said barrel in one of said components, said barrel having means to slidably retain one of said arms and other means to removably retain the other arm of said pair.

3. In combination, a hair curler, a hair pin comprising normally closed juxtaposed arms, and a member rotatably mounted on said curler and having an opening and a slot for holding said arms separated.

4. In combination, a hair curler, a hair pin, a head journaled in said curler and having means for holding adjacent parts of said pin separated, and means to prevent displacement of said head longitudinally of said curler.

5. In combination, a hair curler, a hair pin having a pair of normally closed and juxtaposed arms, a barrel rotatably sustained by said curler and having an opening for removably sustaining one of said arms and including a biased notched portion for removably anchoring the other arm of said pair.

6. In combination, a hair curler having a hingedly associated tube and cover, a hair pin having normally closed juxtaposed arms and

a closure rotatably carried by said tube and including spaced means for disconnectably holding said arms separated with one of said arms laterally separable from said means.

7. In combination, a cover, a tube, fulcrum means hingedly holding said cover and tube, a sleeve within said tube and retained against displacement by said fulcrum means, a barrel comprising an expanded and reduced part, means for rotatably sustaining said expanded part in said sleeve, said reduced part extending longitudinally of said tube and in part projecting therefrom and including means for removably holding the arms of said pin widely separated with one arm of said pin laterally separable from said means.

8. In combination, hingedly associated complementary hair clamping components adapted to wind hair to form a curl, a hair pin having a pair of integrally and resiliently connected and normally closed arms, and unitary means journaled in one of said components for removably holding said arms widely separated, one of said arms having a free part adapted to be laterally displaced from said unitary means, the other arm of said pin being in part removably concealed within said unitary means whereby said curl is adapted to be shifted longitudinally of said components to outwardly displace said free part and be positioned on said other arm upon disengagement of said pin from said unitary means, said laterally displaceable arm upon disengagement of said pin from said unitary means holding said curl on said other arm.

9. In combination, a hair curler comprising a tube and cover, means hingedly connecting said cover and tube, spring means to normally hold said cover closed, a barrel rotatably mounted at one end of said tube and comprising an expanded part within said end and a reduced part extending from said end, said tube having indent means to prevent longitudinal displacement of said barrel in one direction and having other means cooperating with said expanded part to prevent longitudinal displacement of said barrel in an opposite direction, and a hair pin having normally closed arms, said reduced part having spaced means for removably holding said arm widely separated to permit the transfer of a curl from said curler onto said pin and between the arms thereof upon separation of said pin from said curler.

10. In combination, a hair curler having a hingedly associated tube and cover, unitary means mounted at one end of said tube, means rotatably guiding said unitary means at said end, and a hair pin having a pair of resiliently connected and normally closed arms, said unitary means having spaced means for removably holding said arms widely separated; said curler adapted to be rotated relative to said unitary means to form a curl about said tube and cover, said curl adapted to be shifted longitudinally of said tube and cover to be free thereof and be mounted on one of said arms and held thereon by the other arm of said pair upon disengagement of said arms from said unitary means.

11. In combination, a tube comprising a bearing, a cover hinged to said tube, a member rotatably carried by said bearing and in part extending beyond one end of the latter, a hair pin comprising a pair of normally closed arms, means to prevent displacement of said member longitudinally of said tube, said tube and cover upon bodily rotation thereof relative to said member

5 adapted to roll hair and form a curl, said member having spaced means for removably holding said arms widely apart during rotation of said tube and cover relative to said member, said curl adapted to be displaced longitudinally of said cover and tube to outwardly displace one of said arms preparatory to the positioning of said curl upon the other arm of said pair upon disengagement of said pin from said member, said curl adapted to be positioned on said other arm of said pin upon disengagement of said pin from said member and held thereon by said outwardly displaceable arm.

12. In combination, a hair curler comprising a tube having a bearing, a cover hinged to said tube, a member rotatably guided by said bearing and comprising a bore and a notch spaced from said bore, means to prevent displacement of said member longitudinally of said tube, a hair pin having a pair of arms, one of said arms being slidably retained in said bore, the other arm of said pair having an intermediate part adapted to be removably locked in said notch and having a free portion spaced from said curler, said curler adapted to be rotated relative to said member to form a curl, said curl adapted to be shifted from said curler onto said member to outwardly displace said free portion, said curl adapted to be threaded onto said other arm upon separation of said pin from said member and adapted to be held on said other arm by said free portion.

13. In combination, a hair pin having a pair of normally closed arms, a hair curler comprising a tube having a bearing, a cover hinged to said tube, a member rotatably guided by said bearing, said member having a bore extending within the body thereof and a notch disposed along the periphery of said member, said notch having a biased wall in spaced relation to said bore, said bore adapted to slidably guide one of said arms and said notch adapted to slidably and removably guide the other arm of said pair and sustain said last mentioned arm in an oblique relation in respect to said curler whereby said arms are held widely separated, said curler upon rotation thereof relative to said member adapted to form a curl, said curl upon shifting thereof longitudinally of said curler and toward said member adapted to outwardly displace said arm guided in said notch, said arm guided in said bore upon disengagement and separation of said pin from said member adapted to support said curl whereby said arm adapted to be slidably guided by said notch clamps said curl against said arm adapted to be guided by said bore.

14. In combination, hingedly associated complementary hair clamping components, a hair pin, and means at least in part rotatably carried by one of said components and having means for removably sustaining the arms of said pin widely separated.

15. In combination, hingedly associated complementary hair clamping components, a hair pin comprising juxtapositioned arms, and means carried at one end of one of said components and at least in part rotatably sustained by the latter and having a bore to slidably guide one of said arms and a notch including walls to removably retain the other arm of said pin.

16. In combination, hair clamping means comprising a tube and pivoted cover, a hair pin having normally closed arms, means for spreading said arms at one end of said tube, said means being at least in part rotatably sustained at one end of said tube, said clamping means being ro-

tatable relative to the spread relation of said arms during winding of hair about said clamping means in the formation of a curl, said curl being adapted to be moved towards said pin to be threaded on one of said arms upon the removal of said pin from said means whereupon said arms resiliently clamp and straddle a side of said curl.

17. In combination, a resilient hair pin, a hair curler, and rotatable means in longitudinal alinement with said curler and carried thereby for spreading the shanks of said pin.

18. In combination, hair curling means, a resilient hair pin having a pair of shanks, and means at least in part rotatably carried by said curling means for removably sustaining said shanks widely separated.

19. In combination, a resilient hair pin having a pair of shanks and a loop connecting said shanks, a hair curler, and rotatable means in longitudinal alinement with said curler and carried thereby for holding the terminal of one of said shanks outside of said curler and at an oblique angle thereto at a time when the other shank of said pair is at least partly within said rotatable means at which time said loop projects outside of said curler.

20. In combination, a resilient hair pin having a pair of normally closed shanks, a hair curler, rotatable means in longitudinal alinement with said curler and carried thereby, said shanks adapted to be diverged by said rotatable means upon insertion of one of said shanks therein to arrange the other shank of said pair outside thereof, the last mentioned shank having a free unsupported terminal and spatially overlying said curler at an oblique angle in respect to the longitudinal axis thereof.

21. In combination, a hair pin having a pair of normally closed shanks, and a hair curler including rotatable shank spreading means at one end thereof having an opening, one of said shanks adapted to be received in said opening whereby said rotatable spreading means diverges said shanks to dispose the latter in a straddling gripping engagement with said means for arranging the terminal of the other shank of said pair in a free and unsupported relation outside of said curler whereby said curler may be rotated relative to said shanks, said rotatable means being disposed longitudinally of said curler and rotatably sustained by the latter.

22. In combination, a resilient hair pin having a pair of normally closed shanks and a loop connecting said shanks, a hair curler having a rotatable tip including an opening for receiving one of said shanks and including shank spreading means for diverging said shanks to dispose said loop in a closely straddling and gripping and removable engagement therewith, said tip characterizing terminal means disposed longitudinally of said curler at one end thereof, and means rotatably sustaining said terminal means.

23. A curling device having a rotatable end, said end having an opening shaped to receive one shank of a hair pin or bobby pin, said end having means shaped to hold the other shank of the hair pin or bobby pin external to said curling device and at an angle to the longitudinal axis thereof, said rotatable end characterizing terminal means disposed longitudinally of and at one end of said curling device, and means rotatably holding said terminal means.

24. A curling device having a rotatable end, said end having an opening shaped to receive one shank of a hair pin or bobby pin, said end having means shaped to hold the other shank of the hair pin or bobby pin external to said curling device and at an angle to the longitudinal axis thereof, such curling device having a clamping bar movably connected thereto, the tip of said clamping bar being spaced rearwardly from said rotatable end, said end characterizing terminal means, and means rotatably sustaining said terminal means at one end of said device longitudinally thereof.

25. In combination, a resilient hair pin having a pair of normally closed shanks, a hair curler having at one end thereof rotatable means including an opening for receiving one of said shanks and including shank spreading means for diverging said shanks to dispose the latter in a closely straddling and gripping engagement with said means for arranging the terminal of the other shank of said pair in a free and unsupported relation outside of said curler and obliquely relative to the longitudinal axis thereof, said pin having means connecting said shanks and disposed outside of said rotatable means during rotation of said curler relative to said shanks and rotatable means, said rotatable means being disposed longitudinally of said curler at one end thereof, and means rotatably sustaining said rotatable means.

26. In combination, a hair pin having a pair of normally closed shanks, a hair curler having rotatable means including an opening for receiving one of said shanks and including exteriorly disposed spreading means for diverging said shanks to dispose the latter in a closely straddling and gripping engagement with said means for arranging the terminal of the other shank of said pair in a free and unsupported relation outside of said curler and obliquely relative to the longitudinal axis of said curler, said pin having means resiliently connecting said shanks and disposed outside of said means during rotation of said curler relative to said shanks and rotatable means, said rotatable means being disposed longitudinally of said curler at one end thereof, and means rotatably sustaining said rotatable means.

27. In combination, a hair curler, a hair pin having resiliently controlled and normally closed shanks, and rotatable shank spreading means carried by said curler, said spreading means and pin adapted to be held stationary during rotation of said curler and said pin characterizing waiting means for subsequently receiving and clamping a curl previously formed on said curler during rotation of the latter relative to said shanks, said curler having means rotatably sustaining said rotatable shank spreading means at one end and longitudinally thereof.

28. In combination, a resilient hair pin having a pair of normally closed shanks and a loop connecting said shanks, a hair curler, and rotatable means carried by said curler for holding the terminal of one of said shanks outside of said curler and at an oblique angle thereto at a time when the other shank of said pair is at least partly within said rotatable means at which time said loop projects outside of said curler, said curler having means rotatably sustaining said rotatable means at one end and longitudinally thereof.

NATHAN L. SOLOMON.
